UNITED STATES PATENT OFFICE.

SAMUEL ROBERT, OF NEW YORK, N. Y.

DESIGN FOR AN ASH TRAY.

Application filed July 25, 1923. Serial No. 6,854. Term of patent 3½ years.

To all whom it may concern:

Be it known that I, SAMUEL ROBERT, a citizen of the United States, and a resident of the city, county, and State of New York, have invented a certain new, original, and ornamental Design for an Ash Tray, of which the following is a specification, referring had to the accompanying drawing, forming part thereof.

In the drawings,

I claim:

The ornamental design for an ash tray, as shown.

SAMUEL ROBERT.
